US0D1010831S

(12) **United States Design Patent** (10) **Patent No.:** **US D1,010,831 S**
(45) **Date of Patent:** **** Jan. 9, 2024**

(54) **PATIENT CONTROL**

(71) Applicant: **INSPIRE MEDICAL SYSTEMS, INC.**, Golden Valley, MN (US)

(72) Inventors: **Jordan McIver**, Blaine, MN (US); **Douglas Murphy**, Plymouth, MN (US); **Casimir Sienkiewicz**, Minneapolis, MN (US); **Travis Yoch**, Woodbury, MN (US); **Robert Roberts**, Saint Paul, MN (US)

(73) Assignee: **INSPIRE MEDICAL SYSTEMS, INC.**, Golden Valley, MN (US)

(**) Term: **15 Years**

(21) Appl. No.: **29/771,463**

(22) Filed: **Feb. 23, 2021**

(51) **LOC (14) Cl.** **24-02**

(52) **U.S. Cl.**

USPC **D24/186**

(58) **Field of Classification Search**

(57) **CLAIM**

The ornamental design for a patient control, as shown and described.

DESCRIPTION

FIG. 1 is a top, back, right perspective view of a patient control;

FIG. 2 is a back elevational view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the Figures are included for the purpose of illustrating portions of the patient control that form no part of the claimed design.

1 Claim, 7 Drawing Sheets
